UNITED STATES PATENT OFFICE.

JOHN ROGERS FLANNERY, BENJAMIN E. D. STAFFORD, AND ETHAN I. DODDS, OF PITTSBURGH, PENNSYLVANIA, ASSIGNORS, BY MESNE ASSIGNMENTS, TO FLANNERY BOLT COMPANY, OF PITTSBURGH, PENNSYLVANIA, A CORPORATION OF DELAWARE.

MEANS FOR TESTING STAY BOLTS IN BOILERS.

Application filed September 11, 1917. Serial No. 190,786.

To all whom it may concern:

Be it known that we, JOHN ROGERS FLANNERY, BENJAMIN E. D. STAFFORD, and ETHAN I. DODDS, citizens of the United States, and residents of Pittsburgh, in the county of Allegheny and State of Pennsylvania, have invented certain new and useful Improvements in Means for Testing Stay Bolts in Boilers; and we do hereby declare the following to be a full, clear, and exact description of the invention, such as will enable others skilled in the art to which it appertains to make and use the same.

This invention relates to improvements in means for testing stay bolts in boilers,—the object of the invention being to provide simple and efficient means whereby the condition of the bolt may be determined without necessity for removing any portion of the bolt structure.

A further object is to provide electrical means which will operate to indicate or denote the condition of integrity of the bolt while the same is in place in the boiler.

With these and other objects in view, the invention consists in certain novel features of construction and combinations of parts as hereinafter set forth and pointed out in the claims.

In the accompanying drawings, Figure 1 is a view illustrating an embodiment of our invention, and Figure 2 is a view showing a modification.

1 represents a stay bolt for boilers and 2 one of the boiler sheets. The bolt may be of the flexible type, having a rounded head 3 at one end to be suitably mounted at one of the boiler sheets and having its other end threaded through the other boiler sheet 2 and upset.

The bolt is provided with a tell-tale hole or bore 4 which may extend from one end of the bolt approximately to the other end thereof, and terminate within the rounded head 3.

A plug 5 of fire clay or other suitable electrical insulating material is tightly fitted in the open end of the bore 4 and carries the terminals of a coil 6 located within said bore. This coil will preferably be composed of naked wire of comparatively fine gauge with its convolutions electrically spaced from

each other, and said coil may contain an iron core 7, if desired to enhance the generation of current in the circuit of the coil 6. The 55 terminals of the coil 6 which project through the plug 5, are connected with the terminals of a translating device 8.

The coil 6 is embedded within the bore 4 in a mass of material 9 which will, by contact of water, cause the wire of the coil to corrode or be destroyed and thus open the circuit of the translating device. Such will be the result in the event the bolt should become so broken or ruptured as to admit 65 water to the tell-tale hole. The material 9 may consist of a mixture of a sulphate such as sulphate of soda, potash or lime, or crystallized sulphuric acid and a suitable filler, such as chalk.

An electro-magnet is indicated at 10 having its poles applied to the boiler sheet at respective sides of the end of the stay bolt. The coil 11 of this magnet is included in circuit with a source of alternating electric 75 current or in a circuit provided with a suitable interrupter. In the drawings, we have shown the magnet coil included in circuit with the secondary of a transformer 12, the primary of which is connected with a suitable alternating current generator, indicated at 12^a.

When the magnet is applied, as above described, a current will be induced in the coil 6 within the bore of the bolt (if the latter is not ruptured) and this current will operate the translating device to denote the good condition of the bolt. Should the bolt be broken or ruptured so that water has been admitted into the tell-tale hole, the material 9 will have so corroded the wire of the coil 6 as to open the circuit of the same, and hence, when the magnet is applied as above described, no current will be induced in said coil and hence the translating device will 90 not be operated, thus denoting that the bolt is ruptured.

In the operation of our improvements, the boiler plate will become saturated magnetically as will also a portion of the stay bolt and a sufficient number of magnetic lines of force will cut the coil (the convolutions of which are necessarily not parallel but at an angle to the path of the lines of

force) to set up a sufficient current to actuate the translating device and cause a signal to be produced.

In the form of the invention shown in 5 Figure 2, the coil 13 within the bore of the bolt, is electrically connected at one end with the wall of said bore as indicated at 14 and the other end of said coil which extends through the plug 5, is connected with the 10 boiler sheet as indicated at 15. In other respects, the structure shown in Figure 2 may be the same as that shown in Figure 1.

Other slight changes might be made in the 15 details of construction of our invention without departing from the spirit thereof or limiting its scope as defined by the appended claims and hence we do not wish to restrict ourselves to the precise details herein set forth.

20 Having fully described our invention what we claim as new and desire to secure by Letters Patent, is:

1. The combination with a stay bolt having a bore, of a coil within said bore, a 25 material within said bore and contacting with said coil, said material being such as will by contact with moisture cause severance of the wire of said coil, a translating device included in circuit with said coil, and 30 means for inducing an electric current in said coil.

2. The combination with a stay bolt hav-

ing a bore, of a coil within said bore, a translating device in circuit with said coil, an electro-magnet, means for energizing said magnet whereby a current will be induced in 35 said coil when the magnet is applied to the boiler in the vicinity of the bolt, and means within the bore of the bolt for rupturing the circuit of the coil when moisture enters 40 said bore.

3. The combination with a stay bolt having a bore, of a coil within the bore of the bolt, a plug of insulating material closing the end of said bore and through 45 which the terminals of said coil pass, a translating device having its terminals connected with the terminals of said coil, an electro-magnet to be applied to the boiler in vicinity to the bolt, a source of alternating electric current including the coil of the electro-magnet, and a material within 50 the bore of the bolt which will, by contact with moisture, rupture the circuit of said closed coil.

55 In testimony whereof, we have signed this specification in the present of two subscribing witnesses.

JOHN ROGERS FLANNERY.
